(57) **CLAIM**

The ornamental design for a housing of hedge trimmer as shown and described.

DESCRIPTION

FIG. 1 is a front view of a housing of hedge trimmer showing our new design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken line illustrates the bounds of the housing of hedge trimmer and forms no part of the claimed design. The de-emphasized regions within the broken boundaries illustrate portions of the housing of hedge trimmer that form no part of the claimed design.
